[57] **CLAIM**

The ornamental design for a housing for a portable radio communication unit, as shown and described.

DESCRIPTION

FIG. 1 is a front elevation of a housing for a portable radio communication unit showing my new design;

FIG. 2 is a rear elevation thereof;

FIG. 3 is a side elevation thereof;

FIG. 4 is an elevation taken from the side opposite FIG. 3;

FIG. 5 is a top plan view thereof; and

FIG. 6 is a bottom plan view thereof.

The broken lines are shown for illustrative purposes only.

FIG. 1

FIG. 2

FIG. 3

FIG. 4

FIG. 5

FIG. 6
